UNITED STATES PATENT OFFICE.

EUGENE H. PECK, OF MERIDEN, CONNECTICUT, ASSIGNOR TO THE MERIDEN BRONZE COMPANY, OF SAME PLACE.

EXTENSION-LAMP FIXTURE.

SPECIFICATION forming part of Letters Patent No. 389,005, dated September 4, 1888.

Application filed May 21, 1888. Serial No. 274,467. (No model.)

To all whom it may concern:

Be it known that I, EUGENE H. PECK, of Meriden, in the county of New Haven and State of Connecticut, have invented a new Improvement in Extension-Lamp Fixtures; and I do hereby declare the following, when taken in connection with accompanying drawings and the letters of reference marked thereon, to be a full, clear, and exact description of the same, and which said drawings constitute part of this specification, and represent, in—

Figure 1, the invention as applied to an adjustable standard resting upon the floor; Fig. 2, a transverse section through the shoe above the roller; Fig. 3, an open side view of the shoe; Fig. 4, the invention as applied to a telescopic adjustable tube or standard in the reverse position from that seen in Fig. 1—that is, as suspended from the ceiling; Fig. 5, a modification.

This invention relates to an improvement in extension devices for lamps, such as are arranged to be suspended from the ceiling—as chandeliers—or to rest upon the floor, and such as consist of an outer tube with an inner tube or rod working telescopically therein, the outer tube being stationary either upon a base to rest upon the floor or supported from the ceiling, the inner tube or rod carrying the lamp or lamps and made adjustable as to elevation by the movement of the lamp-supporting rod or tube within the outer tube.

In order to support the inner tube at any position to which it may be adjusted, some device or mechanism is necessary between the outer and inner tubes, which will interlock the two, or so engage them that the adjustable tube will stand at any point of elevation to which it may be moved. It is to this engaging mechanism that the invention particularly relates.

I first illustrate the invention as applied to a standard for lamps and other purposes.

A represents an outer tube, supported upon a suitable base, B, in a vertical position. Within this outer tube the inner tube, C, is arranged, so as to slide therein telescopically, and as common in this class of standards. To the lower end of the tube C the shoe D is securely fixed, or may be made a part of the inner tube. The diameter of the shoe corre-

sponds substantially to the internal diameter of the outer tube, but so as to move freely therein as the inner tube, C, is raised or lowered. On one side of the shoe a recess, E, is formed, opening against the inner surface of the outer tube. The bottom of the recess is inclined from the lower end of the shoe upward and toward the open side of the shoe, as represented in Fig. 1.

Before introducing the shoe into the outer tube a spherical roller or ball, F, is placed in the recess, the diameter of which is somewhat greater than the distance from the inner surface of the outer tube to the nearest point of the inclined surface of the side of the recess in the shoe, and as represented in Fig. 1. Below the roller a suitable spring, a, preferably a wire spiral spring, is set, the spring resting upon the lower end of the recess, and the roller stands upon the upper end of the spring, and so that the tendency of the spring is to force the roller upward into the narrower portion of the space between the inner surface of the outer tube and the bottom of the recess in the shoe. The result of this is that normally the inclined surface of the recess works between the ball and the side of the outer tube opposite the opening of the recess—as a wedge—the tendency of which wedging is to force the roller against the outer tube upon the open side of the recess, and as seen in Fig. 1, but when the inner tube is raised the wedge-like part of the shoe is withdrawn, or relieves the roller to such an extent as to permit the inner tube to rise with little obstruction; but upon any attempt to force the inner tube downward the wedging of the shoe upon the roller becomes greater and so as to produce a cramp between the inner and the outer tube, so great as to prevent the descent of the inner tube. To relieve the adjustable inner tube from this cramping operation, so that it may be easily moved downward, a rod, G, is placed within the inner tube, which extends down through the upper end of the shoe, and so as to bear upon the ball or roller F. From this rod any suitable handle, as H, is provided at a convenient point, so that the rod may be forced downward, as indicated in broken lines, Fig. 1, and, bearing upon the ball or roller, will force the ball or roller downward in advance of the shoe,

and thus bring the ball into the greater depth of recess in the shoe, and so as to relieve it from the cramp and permit the rod to be moved freely downward, and this same operation of 5 the rod upon the ball or roller may be applied in raising the inner tube, and thereby relieve the inner tube from the friction which would naturally occur by the upward pressure upon the ball from its spring. The ball or spherical-shaped roller stands free within the recess—that is, without fixed axis—and is therefore free to revolve in any direction. The result 10 of this is that in adjustment the ball will constantly change its position and present an ever-changing bearing-surface between the 15 shoe and inner tube. Consequently the wear which would necessarily follow a roller hung upon an axis is avoided.

The same shoe applies to an extension device 20 for chandeliers, as seen in Fig. 4, it only being necessary to invert the shoe from the position in Fig. 1 to that seen in Fig. 4. In the latter case the outer tube, A, is fixed to the ceiling, while the inner tube, C, carrying the 25 lamps, or whatever it may be, below, hangs from the outer tube.

The adjustable portion of the standard is best made in the form of a tube, as I have described, so that the rod may be placed within 30 the tube, a common construction in this class of devices; but instead of making the adjustable part tubular it may be made a solid rod, as also common in this class of devices, in which case the adjusting-rod will be introduced 35 between the inner rod and the outer tube, as seen in Fig. 5.

I am aware that standards consisting of a stationary tube and a tube telescopically adjustable therein, combined with a device to 40 automatically engage the inner tube with the outer tube, and with a rod extending from such device through the inner tube to a point where

the hand can be conveniently applied to break the connection, so automatically made, between the outer and the inner tube, have long 45 been known in the art in lamp-fixtures and for other purposes, both in standards adapted to be supported upon the floor and others adapted to be supported from the ceiling. I therefore make no claim, broadly considered, 50 to such construction, my invention being for the peculiar construction of the parts, as herein-after particularly recited; neither do I claim, broadly, the employment of a ball as the brake or engaging device between the adjustable and 55 stationary part of the standard.

I claim—

The combination of the stationary outer tube, A, the inner adjustable tube, C, the shoe D, attached to or made a part of the outer tube, 60 the said shoe being within the said outer tube, the said shoe constructed with a recess open to the inner surface of the outer tube upon one side, the side of the recess opposite to the tube being inclined longitudinally toward the open 65 side of the shoe, a spherical roller, F, within said shoe, the diameter of the said spherical roller being greater than the least distance between the said inclined side of the shoe and the opposite side of the inner tube, a spring 70 in the recess of the shoe and upon which the said roller rests, the tendency of the spring being to force the roller to the narrower portion of the recess in the shoe, and a rod, G, extending from said recess and terminating in 75 a suitable handle for moving said rod, the said rod extending into said recess and so as to bear upon said ball opposite said spring, substantially as described.

EUGENE H. PECK.
